Application November 7, 1940, Serial No. 364,647

10 Claims.

(Cl. 40—158)

This invention relates to photography and projection.

The invention provides novel means for filing film and film slides, the filing means being so arranged that the films or slides may be displayed readily and easily and the desired film or slide may be located quickly and withdrawn from the file without the necessity of touching or handling any other film or slide.

The invention will be understood from the following description when considered in connection with the accompanying drawings forming a part thereof, and in which:

Fig. 1 is an elevational view of a film file embodying the invention;

Fig. 2 is a perspective view of a type of film slide which is adapted to be filed and displayed in the file embodying the invention;

Fig. 3 is a sectional view taken on line 3—3 of Fig. 1;

Fig. 4 is a sectional view taken on line 4—4 of Fig. 1;

Fig. 5 is an elevational view of part of the back of the file shown in Fig. 1, and

Fig. 6 is a partial elevational view of another form of file.

Like characters of reference refer to the same or to similar parts throughout the several views.

Referring to the drawings, the form of file shown is arranged to receive twelve films or slides in three parallel rows of four each. However, it will be understood that the file may be arranged to receive any desired number of films or slides, and the number of pockets to receive them in any row and the number of rows may be varied as desired. For example, the file may consist of a single row of pockets. The word "film" as used herein and in the claims, is intended to include within its scope, film slides and the like.

Preferably the file is made of cardboard of a neutral color, but other suitable materials may be employed. In the form shown, the file is rectangular in form and consists of three sheets of cardboard suitably formed and glued together. The front sheet 10 provides the front cover for the file and it is cut to provide horizontally extending doors or flaps 11, each of which swings about its lower edge as shown. The hinge for each door or flap preferably is an uncut portion of the front sheet or a portion which is cut only part way through the sheet from the rear toward the front. Other hinge means may be employed.

The intermediate sheet 12 is of approximately the thickness of the film or slide 18, Fig. 2, to be

received in the file and it is cut to form the requisite number of pockets 13 for the film, each pocket having a cut-out portion 14 into which a fingernail or other means may be inserted to facilitate the removal of the film in that pocket. The size of each pocket is such that the film slide fits fairly snugly therein, as shown. Preferably however, the sides of each pocket flare outwardly slightly from the bottom to the top, and the distance between the lower side edges of the pocket is such as to provide a friction grip with the lower side edges of the film. The rear sheet 15 provides the back wall of the pockets. For each pocket, the front and rear sheets 10 and 12 have cut-out portions 16 and 17 respectively, of Greek cross configuration which are approximately the same size for each arm of the cross, as the film in a film slide such as the slide 18, and these cut-out portions are located so as to register with each other and to be centrally disposed with respect to the pockets 13. With cut-out portions of this configuration, the film slide may be placed in the pocket with the horizontal axis of the slide either horizontal, as shown in the first pocket from the left in the top row in Fig. 1, or vertical as shown in the second pocket from the left in the top row in Fig. 1. The hinged portion 19 of each of the flaps 11 is located above the lower edge 20 (Fig. 4) of the pockets 13 so that the slides will be retained in the pockets even when the flaps are in open position.

Means are provided to retain the doors or flaps 11 in closed position. To this end, the upper central part of each door or flap 11 is provided with a projecting portion or extension 21 which is received in a similarly shaped cut-out portion 22 in the front sheet 10 of the file. As shown, the extension has an upper edge parallel to the upper edge of the flap, with sides which are inclined toward each other and join the upper edge of the flap and extension with smooth curves. This extension may be of any other convenient shape or size suitable for the purpose. An elastic band 23 extends across the extension 21 and passes through openings 24 in the file at opposite sides of the cut-out portion 22 and into elongated recesses 25 in the rear face of the file provided by registering apertures in the intermediate and rear sheets 12 and 15. Each end of the elastic has a metallic clip 26 secured thereon which is received in the recess 25 to retain the elastic band in position. If desired, the ends of the elastic bands may be knotted in lieu of using the clips 26, or any other suitable means may be employed for the purpose.

Inasmuch as the flaps 13 have no projecting portions when they are in closed position, means are provided to facilitate their movement to open position in order that films may be inserted in and removed from the file. As shown, each end portion of each flap is shaped to provide an extension 27 of approximately triangular configuration with the base of each extension at the upper edge of the flap. Rear sheet 15 is apertured at 28 in registry with the extensions 27 to permit a finger to be inserted through the aperture from the rear of the file and to press the flap into open position. The intermediate sheet 12 is cut away in the region of the apertures 28, so as not to obstruct these apertures. When it is desired to move a door or flap 11 to open position, the elastic band is merely displaced upwardly a distance sufficient to free the extensions 21, and the flap is opened by inserting a finger or an object in an aperture 28 and pushing the flap open. When the flap is to be closed, the elastic band is displaced upwardly sufficiently to permit the extension to enter the recess 22, after which the band is released and it will assume its normal position across the extension.

Each file has a plurality of holes 29 so that the file may be inserted and retained in a ring binder of any suitable type. Any other suitable binding or holding means may be utilized however, in lieu of the ring binder.

In the form shown in Fig. 6, the door or flap 11, has an extension 30 of the general configuration of a dove-tail which fits snugly into a similarly shaped recess in the front sheet 10 of the file. The sides of the extension are outwardly flaring and will prevent opening of the flap in the event of any shrinkage in the flap. This form of flap may be used with an elastic band if desired, or with any other positive means for retaining the flap in closed position.

In use, the film is placed in the desired pockets of the file in the proper position, and in the desired order. If the files are retained in a ring binder, to find a particular film, it is only necessary to place the binder in such a position that light, either natural or artificial, will shine on the back of the files as they are turned in the binder, with the user viewing the files from the front thereof. Thus, the light will fall directly on the film and they may be recognized readily so that the film or films to be located will be found quickly. The films may be displayed in a similar manner. If a binder or the like is not used, the files may be placed one at a time between a source of light and the user, and the desired film may be found quickly, or displayed.

The lower portion of the front or rear wall of each pocket, or both these walls may be provided with projecting portions which extend inwardly of the pocket which will frictionally engage the film and retain it in the pocket. With the arrangement illustrated, the film will be retained in the pockets even when the doors or flaps 11 are open, because of the friction between the film and the walls of the pockets. If desired, the file may be composed of separate strips, such as one of the horizontal rows of pockets in the form of the invention illustrated, and a plurality of these separate strips may be held together in a frame of light metal, or other suitable material.

It will be apparent to those skilled in the art, that changes may be made in the form of the invention disclosed, as well as in the shape or composition of the several parts thereof, and

their relative arrangement, without departing from the principles of the invention. Accordingly, it will be understood that the invention is not to be limited excepting by the scope of the 5 appended claims.

What is claimed is:

1. A film file having a body portion and a film pocket therein, opposite outer walls of the pocket having registering apertures disposed to register with a film placed in the pocket to permit the film to be seen while in the pocket, an outer wall of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, and means carried by the body portion and cooperable with said extension for releasably retaining the movable wall in closed position.

2. A film file having a body portion and a film pocket therein, opposite outer walls of the pocket having registering apertures disposed to register with a film placed in the pocket to permit the film to be seen while in the pocket, an outer wall of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, and elastic means carried by the body portion and cooperable with said extension for releasably retaining the movable wall in closed position.

25 3. A film file having a body portion and a film pocket therein, opposite outer walls of the pocket having registering apertures disposed to register with a film placed in the pocket to permit the film to be seen while in the pocket, an outer wall of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, and elastic means carried by the body portion and cooperable with said extension for releasably retaining the movable wall in closed position.

30 4. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, and an elastic band carried by the body portion and positioned

35 with said extension for releasably retaining the movable wall in closed position.

5. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

40 6. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

45 7. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

50 8. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

55 9. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

10 10. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

11 11. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

12 12. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

13 13. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

14 14. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

15 15. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

16 16. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

17 17. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, and an elastic band carried by the body portion and extending through said apertures and normally across said extension when said movable wall is in closed position to retain the movable wall releasably in closed position.

to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, an elastic band carried by the body portion and extending through said apertures and normally across said extension when said movable wall is in closed position to retain the movable wall releasably in closed position, said body portion having a recess communicating with each aperture, and means on each end portion of the elastic band and receivable in said recesses to retain the band in position on the body portion.

6. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension, said body portion having a recess shaped similarly to said extension to receive said extension, said body portion having an aperture adjacent opposite sides of the extension, an elastic band carried by the body portion and extending through said apertures and normally across said extension when said movable wall is in closed position to retain the movable wall releasably in closed position, said body portion having a recess communicating with each aperture, and a metallic clip on each end portion of the elastic band and receivable in said recesses to retain the band in position on the body portion.

7. A film file having a body portion and a film pocket therein, opposite outer walls of the pocket having registering apertures shaped and disposed to register with a film placed in the pocket in either a horizontal or a vertical position to permit the film to be seen while in the pocket in either of said positions, one of the outer walls of the pocket being hingedly movable with respect to the body portion and otherwise free of attachment thereto to permit the insertion of film in the pocket and its withdrawal therefrom, the movable wall having a snug fit with the body portion when in closed

position, and the body portion having an aperture in registry with a portion of the movable wall to facilitate movement of the movable wall to open position.

5 8. A film file having a plane body portion and a plurality of film pockets therein, opposite outer walls of each pocket having apertures in the general form of Greek crosses and in substantial registry and disposed to register substantially with a film placed in the pocket with its longer dimension substantially parallel to either axis of the Greek cross apertures, to permit the film to be seen while in the pocket, an outer wall of one pocket being integral with an outer wall of at least one other pocket, said last mentioned wall being movable to permit the insertion of film in the pockets and its removal therefrom.

20 9. A film file having a body portion and a plurality of film pockets therein, opposite outer walls of each pocket having registering apertures disposed to register with a film placed in the pocket, each pocket being arranged to receive and to retain a film therein, an outer wall of one pocket being integral with an outer wall of another pocket and being hingedly movable with respect to the body portion and otherwise free of attachment thereto to permit the insertion of film in the pockets and its removal therefrom, said outer wall having an extension projecting from the edge opposite the edge about which it is hingedly movable and provided with oppositely inclined sides, and said body portion having a recess shaped similarly to said extension and of a size to receive said extension snugly and to aid in retaining said wall in closed position.

25 10. A film file having a body portion and a film pocket therein, opposite outer walls of the pocket having registering apertures disposed to register with a film placed in the pocket to permit the film to be seen while in the pocket, one of the outer walls of the pocket being hingedly movable with respect to the body portion and otherwise free of attachment thereto to permit the insertion of film in the pocket and its withdrawal therefrom, the movable wall having an extension projecting from the edge opposite the edge about which it is hingedly movable, the side walls of the extension being inclined in opposite directions, and said body portion having a recess shaped similarly to said extension and of a size to receive said extension snugly and to aid in retaining said wall in closed position.

40 WILLIAM N. DE SHERBININ.
